UNITED STATES PATENT OFFICE.

GEORGE E. MOLYNEUX, OF BAYONNE, NEW JERSEY, ASSIGNOR TO THE SINGER MANUFACTURING COMPANY, A CORPORATION OF NEW JERSEY.

FEEDING MECHANISM FOR SEWING-MACHINES.

1,146,437.

Specification of Letters Patent. Patented July 13, 1915.

Application filed June 25, 1913. Serial No. 775,639.

To all whom it may concern:

Be it known that I, GEORGE E. MOLYNEUX, citizen of the United States, residing at Bayonne, in the county of Hudson and State 5 of New Jersey, have invented certain new and useful Improvements in Feeding Mechanism for Sewing-Machines, of which the following is a specification, reference being had therein to the accompanying drawings.

10 This invention relates to an improvement in feeding mechanism and is designed more particularly for embodiment in such mechanism employed for feeding the work longitudinally of the work-support of a cylinder-bed machine.

15 It has for its object partly to provide strong and rigid supporting means for the feed-dog so as to prevent excessive springing of the latter in engagement with the work, and partly to provide a convenient 20 and effective means of adjustment for the length of throw of the feed-dog in advancing the work to space the stitches.

25 In the preferred form of the improvement, the machine has a rotary shaft passing through the hollow standard and the tubular work-supporting arm and carrying within the standard the feed-actuating eccentric and within the work-supporting arm 30 two longitudinally spaced feed-lift eccentrics. The feed-actuating eccentric has a driving connection with said shaft and is fitted upon a bushing which is sustained by and circularly adjustable upon said shaft 35 and provided with means for temporarily detaining it against rotation with the shaft whereby its position of adjustment thereon may be varied to correspondingly change the position of the eccentric radially upon 40 the shaft when the latter is turned in the required direction during the detention of said bushing.

45 At other times, the bushing rotates with the shaft. The feed-actuating eccentric is embraced by a strap at one end of a pitman whose opposite end is connected with one arm of a rocker mounted upon a fixed fulcrum-stud and having a second arm connected by a link with the rearward end of the feed-bar carrying the feed-dog to 50 which it imparts the usual to-and-fro feeding movements.

The feed-bar is slidingly mounted in spaced bearing members sustained at the upper ends of posts having at their opposite

ends straps each embracing one of the feed-lift eccentrics, thereby maintaining the feed-bar in substantial parallelism with the work-support. It is obvious, however, that the relative lengths of the supporting posts may be varied or the relative throw of the feed-lift eccentrics modified to correspondingly change the position and character of movement of the feed-bar, if desired.

55 In the accompanying drawings, Figure 1 is a side elevation, partly in section, of the lower portion of a cylinder-bed machine of the well-known Singer type and constructed substantially in accordance with my application Serial No. 593,796, filed November 23, 1910. Fig. 2 is a plan, partly in section, of the feeding mechanism. Fig. 3 is a perspective view of a portion of the feed mechanism and the main-shaft, showing the means of adjustment of the feed-actuating eccentric. Fig. 4 is an end view of the eccentric bushing, Fig. 5 a perspective view, and Fig. 6 a face view of the feed-actuating eccentric and its carrier, and Fig. 7 is a perspective view of one of the feed-bar sustaining posts.

60 As represented in the drawings, the machine is constructed with a frame comprising the hollow standard 1 to one side of which is secured the tubular work-supporting arm or cylinder-bed 2 passing through which is the main-shaft 3 journaled in suitable bearings and carrying at its rearward end the belt-pulley 4 formed with the cylindrical rim 5. At its outer end the arm 2 is provided with the removable end cap 6 and with the throat-plate 7 through which reciprocates the needle 8 carried by the needle-bar 9, and upon which rests the presser-foot 10 whose shank 11 is secured to the presser-bar 12.

65 The throat-plate has the usual apertures 13 through which pass the serrated work-engaging feeding members 14 of the feed-dog whose shank 15 is adjustably secured by means of the screw 16 within a recess of the block 17 upon the forward end of the feed-bar 18 having at its rearward end the block 19 carrying the pivotal stud-screw 20. To the feed-bar 18, between the blocks 17 and 19, are fitted the bearing sleeves 21 each provided with the transversely extending bosses 22 and pivotally mounted by means of the stud-screws 23 between the divergent arms 24 of the post whose opposite end is formed

with a split sleeve or strap 25 embracing one of two spaced feed-lift eccentrics 26 upon the shaft 3.

The stud-screw 20 passes through the apertured extremity of the block 27 adjustably secured upon one end of the bent pitman rod 28 whose opposite end is provided with a strap 29 having a spherical socket to embrace the ball-stud 30 upon one arm 31 of the plural-armed rocker having its tubular hub 32 journaled upon the fulcrum-stud 33 sustained by the lug 34 upon the inner wall of the standard 1. A second arm 35 of said rocker is provided with the ball-stud 36 upon which is fitted the strap 37 at the outer end of an eccentric rod 38 whose opposite end is formed with the strap 39 embracing the feed-actuating eccentric 40 which is formed at one edge with the lateral flange 41 having the oppositely extending apertured ears 42.

Substantially as shown in my Patent No. 1,024,691, of April 30, 1912, the shaft 3 has secured thereon within the hollow standard 1 the collar 43 provided with the flange 44 having in the present instance the diametrically arranged segmental slots 45 entered by the shanks of the shouldered screw-studs 46 tapped into the ears 42 of the eccentric-flange 41. The eccentric 40 is formed in the face opposite the flange 41 with the elongated bearing cavity 47 in substantial alinement with the stud-screws 46 and slightly offset from the axis of the eccentric, as indicated more particularly in Fig. 6. Within this cavity is fitted the peripheral bearing face of an eccentric sleeve 48 loosely fitted upon the shaft 3 and provided at one edge with the circular flange 49 having the laterally projecting rim 50 formed with the peripheral detent notch 51. The notch 51 is adapted to be entered by the inwardly projecting tooth 52 upon the head 53 of a plunger-pin 54 journaled within the tubular socket member 55 which enters a suitable aperture in the rear wall of the standard 1 and having a foot 56 secured within a countersunk recess 57 in the rear face of the standard by means of the screw 58.

The socket of the member 55 is shouldered in its outer portion to receive one end of the spring 59 surrounding the plunger-pin 54 and having its opposite end in contact with a shoulder formed by a nut 60 applied to the reduced and threaded outer end of the plunger-pin. As represented in Figs. 1 and 3, the rim 5 of the belt-pulley is provided upon one side with a series of graduations forming a scale 5' and is overhung by the wedge-shaped extremity 61 of a pin 62 projecting from the rear cover-plate 63 of the standard and serving as a pointer or index-finger.

The spring 59 normally maintains the plunger-pin retracted and the detent tooth 52 withdrawn from the notch 51 of flange

50, but by pressure upon the nut 60, the tooth 52 may be manually brought into contact with the rim 50 so as to enter the notch 51 when the belt-wheel 4 is turned by hand. When the eccentric sleeve 48 is thus locked against movement, the further turning of the belt-wheel, and hence of the shaft 3, will serve to shift its position circularly relatively to its supporting shaft and correspondingly change its relation with the feed-actuating eccentric 40 which will be thereby shifted toward or from the axis of the shaft and the eccentricity of its operative face changed accordingly. As the scale 5' will assume operative relation with the pointer 61 when the sleeve becomes locked against rotation, the scale and pointer will indicate the throw or extent of operative movement of the eccentric for the adjustment in which the bushing 48 is set.

The object of the elongated form of the cavity 47 is obviously to afford clearance for relative movement of the bushing 48 and the eccentric 40 upon one diameter while they are locked for concurrent movement upon a diameter at right angles therewith and parallel with the slots 45 of the flange 44. As will be observed, the bushing 48 is normally prevented against turning relatively to the shaft by its friction with the latter and with the eccentric 40, the latter being frictionally held in position upon the flange 44 by the stud-screws 46.

The cavity 47 is so positioned relatively to the outer face of the eccentric 40 that when the bushing 48 is in one extreme position the eccentric 40 has its minimum throw, and when the bushing 48 is shifted into the opposite extreme position the eccentric will have its maximum throw.

The operation of the feeding mechanism as thus described will be obvious without further description.

Having thus set forth the nature of the invention, what I claim herein is:

1. In a sewing machine, in combination, a shaft, a feed-bar, actuating means for imparting endwise movements to said feed-bar, a plurality of lifting elements mounted upon and spaced apart endwise of said shaft, and a plurality of members independent of said actuating means engaging said lifting elements and each connected with and affording a support for said feed-bar.

2. In a sewing machine, in combination, a shaft, a feed-bar, means for imparting to said feed-bar endwise movements, a plurality of eccentrics fixed upon and spaced apart endwise of said shaft, and a plurality of posts each formed with a strap embracing one of said eccentrics and having a connection with said feed-bar.

3. In a sewing machine, in combination, a shaft, a feed-bar, an actuating element upon said shaft, a connection between said

element and the feed-bar and including a link pivotally attached to the latter for imparting to it endwise movements, a plurality of lifting elements fixed upon and spaced 5 apart endwise of said shaft, and feed-bar sustaining members engaging said lifting elements.

4. In a sewing machine, in combination, a shaft, a feed-bar, a feed-actuating eccentric mounted upon said shaft, a plural- 10 armed rocker having one arm operatively connected with said eccentric, a link connection between another arm of said rocker and said feed-bar, a plurality of feed-lift 15 eccentrics fixed upon and spaced apart end- wise of said shaft, and sustaining members each provided with a strap embracing one of said feed-lift eccentrics and connected with and affording a support for said feed- 20 bar.

5. In a sewing machine, in combination, a shaft, a feed-bar, an eccentric bushing mounted upon and circularly adjustable relatively to said shaft, a feed-actuating ele- 25 ment mounted upon said bushing, a driving

connection between said element and shaft, and an operative connection between said element and the feed-bar.

6. In a sewing machine, in combination, 30 a shaft, a feed-bar, a feed-actuating eccentric formed with an elongated aperture embracing said shaft, an eccentric bushing journaled upon and frictionally held against rotation on said shaft and entering and contacting with the opposite walls of the aperture of said eccentric, means for detaining said bushing while the shaft is turned to shift it circularly thereon, a driving connection between said eccentric and shaft, and an operative connection between the feed- 40 bar and said eccentric and including a strap embracing the latter.

In testimony whereof I have signed my name to this specification, in the presence of two subscribing witnesses.

GEORGE E. MOLYNEUX.
